Application January 4, 1950, Serial No. 136,714

15 Claims. (Cl. 315—39)

1

This invention relates to electron-discharge devices, and more particularly to microwave oscillation generating devices of the magnetron type.

Magnetrons are usually operated at one of a plurality of discrete frequencies known as modes. The most common operating mode is known as the π mode where alternate anode members are maintained at the same instantaneous potential, and the oscillating potential occurs between adjacent anode members. In modes adjacent the π mode, alternate anode members vary from each other in potential, said varying potentials forming a substantial sinusoidal wave traveling around the anode structure. A resonant mode occurs when the wave traveling around the anode structure returns to its starting point at such a phase that it will reinforce itself. Since the aforesaid phase varies considerably with frequency, and reinforcement and hence oscillation occur when the instantaneous wave voltages of the anode structure vary through a multiple of 360 degrees during one traverse around the anode structure, it may be seen that a plurality of possible oscillation modes exist, said modes being separated by discrete frequencies.

When percentage frequency separation between the operating mode such as the π mode and an adjacent mode is undesirably small, the magnetron will tend to oscillate in the adjacent mode and sap energy from the desired operating mode. Further if the load impedance into which the magnetron is working varies somewhat, the magnetron may shift its frequency from the desired operating mode to the adjacent mode.

In order to increase the power output from a magnetron, the number of anode members must, in general, be increased, since the power output per anode member is limited by the heat dissipating ability of the anode member. However, an analysis of the anode structure of a conventional double strapped cavity magnetron shows that an increase of the anode members results in a decrease in mode separation. Thus, the maximum power output which could be developed by magnetron structures has, in prior designs, been limited by the available mode separation of the magnetron.

The present invention discloses a novel magnetron anode structure wherein the mode separation is considerably greater than in conven-

2

tional designs. This is accomplished by making the anode members of hollow tubes, each tube being supported at two points substantially a half wave length apart. The tubes are spaced around the axis of the magnetron and are parallel thereto. The midpoints of adjacent tubes are connected to the opposite surfaces of a radial transmission line whose effect is to increase the mode separation of the magnetron and, in addition, to act as an output coupling device.

The radial transmission line is shorted substantially a quarter wave length away from the anode members so that it will resonate at the same frequency as the anode members. By the use of this structure, a larger number of vanes may be used without encountering undesirably small mode separation.

In addition, since the anode members are in the form of tubes, a coolant may be circulated through the tubes, thereby further increasing the power which may be generated per anode member. Also, conditions are favorable for power generation by interaction of the electron stream for a relatively large distance on each side of the midpoints of the anode members so that an extended cathode may be used, whereby a larger surface of each anode member is presented to the electron stream than was heretofore possible through the resultant increase in the power dissipating ability of the anode member and an attendant increase in the power output for each anode member.

Other and further advantages of this invention will be apparent as the description thereof progresses, reference being had to the accompanying drawings, wherein:

Fig. 1 illustrates a longitudinal, cross-sectional view of one species of the device embodying this invention taken along line 1—1 of Fig. 2;

Fig. 2 illustrates a transverse, cross-sectional view of the device shown in Fig. 1 taken along line 2—2 of Fig. 1;

Fig. 3 illustrates a modification of the species shown in Fig. 1; and

Fig. 4 illustrates a graph showing operational characteristics of the device shown in Figs. 1 and 2.

Referring now to Figs. 1 and 2, there is shown

50 a magnetron structure comprising a plurality of

parallel, tubular anode members 10 which are spaced around the axis of the magnetron parallel thereto. The upper ends of the tubes 10 extend through an upper end plate 11 which is tightly sealed to tubes 10 by any desired means, such as soldering. The lower ends of tubes 10 extend through a lower end plate 12 and are sealed therein in a manner similar to their sealing in upper end plates 11. The distance between upper and lower end plates 11 and 12 is made substantially equal to a half wave length of the desired operating frequency of the magnetron.

A radial transmission line comprising upper and lower parallel, planar conducting members 13 and 14, respectively, is connected to substantially the midpoints of the anode members 10 in the following manner. One set of alternate anode members is attached to the upper guide member 13, while the other set of alternate anode members, which comprises anode members adjacent the anode members of the first set, is connected to the lower guide member 14. Guide members 13 and 14 are in the form of disks, substantially a half wave length in diameter, extending inwardly from the anode members 10 to the axis of the magnetron.

An output coupling member 15 is connected to the radial wave guide. The output coupling comprises a tube 16 extending through an aperture in the center of upper guide member 13 and connecting to lower member 14. Tube 16 extends upwardly through and is sealed to upper end plate 11. Inside tube 16 and coaxial therewith is a central conductor 17, one end of which extends through an aperture in the side wall of tube 16 between guide members 13 and 14 and is welded to member 13 thus forming the pickup loop. The other end of conductor 17 extends out through the end of cylinder 20 and is insulatedly supported therefrom as, for example, by a glass seal 18.

Surrounding the entire group of anode members, coaxial with the axis of the magnetron and spaced from said anode members, is a cathode structure 19 comprising a metallic cylinder 20, the inner surface of which is coated with electron-emissive material 21. Around cylinder 20 there is wound a heater coil 22 which is imbedded in a coating of insulating material 23 such as, for example, Alundum. The cathode structure 19 is supported at its upper and lower ends by a pair of ceramic rings 24 and 25, respectively.

Lower ceramic ring 25 rests upon lower end plate 12, and upper ceramic member 24 is resiliently urged downward against the top of the cathode structure 19 by means of an annular spring 26 positioned between ceramic ring 24 and upper end plate 11. One end of the heater wire 22 is connected to the cylinder 20, as by welding, and the other end of the heater wire is connected to a lead-in conductor 27 which extends through lower ceramic member 25 and a cylindrical member 28 sealed into an aperture in lower end plate 12. Conductor 27 is insulatedly supported from cylinder 28 by a glass seal 29 at the end of member 28. The cylinder 20 is connected to a lead-in member 30 which extends through ceramic member 25 and a tubular member 31 sealed in an aperture in lower end plate 12. Conductor 30 is insulatedly supported with respect to

member 31 by means of a glass seal 32 in the end of member 31.

Surrounding the cathode 19 and ceramic supports 24 and 25, there is a cylindrical member 33 which is attached to both upper and lower end plates 11 and 12, as by soldering, thereby producing a gas-tight enclosure within the magnetron. A magnetic field is produced in the space between anode members 10 and cathode cylinder 20 by any desired means, such as a coil 34, wound around the outside of cylinder 33 and concentric therewith, through which a suitable direct current is passed. Anode members 10, which are hollow, pass out through end plates 11 and 12 and terminate in upper and lower hollow annular rings 35 and 36, respectively. Upper ring 35 has an inlet pipe 37 connected thereto, whereby a coolant such as, for example, water, may be introduced into the ring 35 and thereby fed through the anode members 10. The coolant upon passing through anode members 10 will collect in lower ring 36 and may be carried off by an exhaust pipe 38 connected thereto.

With a suitable heater voltage applied between conductors 27 and 30, a suitable anode voltage applied between conductor 30 and the anode structure, and a suitable magnetic field applied by means of a current through coil 34, the magnetron will oscillate. An analysis of the mode separation which may be achieved by this structure may be made as follows.

The voltage distribution around the anode members of the magnetron will be sinusoidal and of the form

$$E = E_{\max} \sin n\phi \quad (1)$$

where E is the instantaneous voltage generated during a traverse around the anode structure, $E_{\max}$ is the maximum voltage generated during the traverse around the anode structure, n is the number of the mode, being 0 for the π mode, and 1 for the mode adjacent the π mode etc., and ϕ is the physical angle of rotation around the axis of the anode structure.

The voltage distribution in the radial transmission line for a traverse around all the anode members is also of the form

$$E = E_{\max} \sin n'\phi \quad (2)$$

where n' denotes the number of complete cycles of variation of voltage in the angular direction around the radial transmission line. Therefore, in corresponding modes where $n=n'$, the instantaneous potential of the anode members is similar to the instantaneous potential of the wave traveling in the radial wave guide with the result that impedance matching between the wave guide and the anode members is uniform around the anode members.

Solutions of the input impedance to the radial transmission line may be obtained from field theory. For the $n'=0$ mode, the total input impedance for a radial transmission line, which is short circuited at its output end, is:

$$Z_{n'=0} = -\frac{jdR_c}{2\pi b} \frac{J_o(ka) - \frac{J_o(ka)}{N_o(ka)} N_o(ka)}{J_{o'}(kb) - \frac{J_o(ka)}{N_o(ka)} N_o(kb)} \quad (3)$$

For the $n'=1$ mode, the input impedance for a radial transmission line, which is short circuited at the output end, is:

$$Z_{n'=1} = -\frac{jdR_c}{2\pi b} \frac{2[J_1(kb)N_1(na) - J_1(ka)N_1(kb)]}{J_o(kb)N_1(ka) - J_2(kb)N_1(ka) - J_1(ka)N_o(kb) + J_1(ka)N_2(kb)} \quad (4)$$

where

$J_n(\cdot)$ indicates Bessel Function of first kind and n the order.

$N_n(\cdot)$ indicates Bessel Function of second kind and n the order.

' signifies the derivative.

$k=2\pi/\lambda$.

λ =wave length.

a =outer radius. $R_c=377$ ohms.

b =inner radius.

d =separation of plates.

The total input impedance to the magnetron anode members, as seen by the radial transmission line, is:

$$Z_a = Z_0 N/4 \quad (5)$$

where

Z_a is the total anode input impedance;

Z_0 is the characteristic impedance of a pair of adjacent anode members; and

N is the number of anode members.

A plot of Formulas 3, 4 and 5 appears in Fig. 4 wherein impedance is plotted along the axis of ordinates, and wave length in centimeters is plotted along the axis of abscissae. The curve 39 is a plot of the impedance of the radial transmission line vs. frequency for the $n'=0$ mode given by Equation 3. It may be seen that this curve goes to infinity at a wave length of 10 centimeters which is the π mode. Curve 40 is a plot of the impedance of the anode members vs. frequency as given by Equation 5. As shown here, positive values of the anode impedance are plotted as negative impedances and negative values are plotted as positive impedances. This curve also is discontinuous by passing to infinity at the π mode. Curve 41 is a plot of the impedance vs. wave length for a mode of propagation in the radial transmission line which is the $n'=1$ mode given by Equation 4. This mode has an impedance characteristic which is discontinuous by passing to infinity at a wave length somewhat greater than that of the π mode. For this reason the curve 41 intercepts the curve 40 at a wave length greater than that of the π mode, as shown by point 42. At this point the reactive impedance of the radial transmission line which is positive is just equal and opposite to the reactive impedance of the anode members which is negative although plotted here as positive, and the resultant sum of these reactive impedances is zero thus defining a condition of resonance. As may be seen from the graph, this condition of resonance occurs at approximately 8.6 centimeters or approximately 1.4 centimeters away from the π mode. The mode separation ratio is, therefore, 1.4 to 10 or 14 per cent. This is a considerably greater mode separation than can be obtained in a conventional double strapped magnetron.

Referring now to Fig. 3, there is shown a modification of the device shown in Figs. 1 and 2, wherein the cathode is positioned inside the anode members and the radial transmission line is positioned outside the anode members. The anode members, coolant intake and exhaust structure, and magnetic field structure are similar to that of Figs. 1 and 2. However, a cathode is positioned inside the anode members 10 instead of the radial transmission line. The cathode comprises a metal cylinder 43 spaced from anode members 10 and surrounded thereby. The outer surface of cylinder 43 is covered by electron-emissive material. The upper and lower

ends of cylinder 43 are closed by upper and lower end plates 45 and 46, respectively. The lower end plate 46 has attached to the center thereof a hollow support cylinder 47 which extends through a metal cylinder 48 sealed into an aperture in the lower end plate 12. Cylinder 47 is rigidly supported with respect to cylinder 48 by means of a glass seal 49. Inside cylinder 43 there is wound a heater coil 44, one end of which is attached, as by welding, to cylinder 43, and the other end of which is connected to a lead-in member 45 which extends through cylinder 47 coaxial therewith, and is rigidly supported with respect thereto by means of a glass seal 50. The support and lead-in structure of the cathodes of Figs. 1 and 2, as well as the cathode of Fig. 3 just described, are shown by way of example only, and any desired cathode structure which will produce the desired electron emission adjacent the anode members 10 may be used.

Positioned outside the anode members 10 is the radial transmission line comprising upper and lower planar members 51 and 52, respectively, upper member 51 being connected to one group of alternate anode members adjacent the midpoints thereof, and the lower member 52 being connected to the other group of alternate anode members in a manner similar to that described in connection with the radial transmission line of Figs. 1 and 2. The outer edges of members 51 and 52 are connected to the cylinder 33 comprising the envelope of the magnetron. The distance between the cylinder 33 and the anode members along the transmission line is made substantially equal to a quarter wave length at the desired operating frequency. Thus, the transmission line, being shorted at its outer end by cylinder 33, will resonate at the same frequency as will adjacent pairs of anode members 10, thereby producing an oscillatory structure. An output coupling loop 53 may be inserted through cylinder 33 in a well-known manner.

An analysis of this structure may be undertaken by the same procedure as that illustrated in connection with Figs. 1 and 2. However, the mode separation produced by this structure will be somewhat less than that produced by the structures of Figs. 1 and 2.

This completes the description of the particular embodiment of the invention disclosed herein by way of illustration. However, many modifications thereof will be apparent to persons skilled in the art without departing from the spirit and scope of this invention. For example, the anode members could be supported at one end only and be made substantially a quarter wave length long, or any multiple thereof, and the radial transmission line could be made other multiples of a quarter wave length, and other coupling means could be used for extracting power from the device. Therefore, applicant does not wish to be restricted to the specific details of the species of the invention illustrated herein except as defined by the appended claims.

65 What is claimed is:

1. An electron discharge device comprising a cathode, an anode structure spaced from said cathode, a radial transmission line comprising substantially planar members connected to said anode structure for coupling energy between said anode structure and said transmission line, adjacent anode members being connected to opposite bounding surfaces only of said transmission line, and means adjacent said anode structure for producing a magnetic field between said cathode

and anode structure perpendicular to the direction of motion of electrons from said cathode to said anode structure.

2. An electron discharge device comprising a cathode, an anode structure spaced from said cathode comprising a plurality of anode members, and a radial transmission line comprising a pair of substantially parallel planar conductors, adjacent anode members being connected to opposite bounding surfaces only of said transmission line.

3. An electron discharge device comprising a cathode, an anode structure spaced from said cathode comprising a plurality of anode members, each of said anode members extending in a direction parallel to the electron emitting surface of said cathode for a distance substantially equal to a multiple of a half wave length of the operating frequency of said device, and a radial transmission line connected to said anode members with adjacent anode members being connected to opposite bounding surfaces only of said transmission line for coupling energy between said anode structure and said transmission line.

4. An electron discharge device comprising a cathode, an anode structure spaced from said cathode comprising a plurality of anode members, each of said anode members extending in a direction perpendicular to the electron path between said cathode and said anode structure for a distance substantially equal to a multiple of a quarter wave length of the operating frequency of said device, and a radial transmission line connected to said anode members adjacent the mid points thereof, adjacent anode members being connected to opposite bounding surfaces only of said transmission line.

5. An electron discharge device comprising a cathode, an anode structure spaced from said cathode comprising a plurality of anode members, a radial transmission line comprising a pair of substantially parallel disk portions, adjacent anode members being connected to opposite bounding surfaces only of said transmission line, and means adjacent said cathode for producing a magnetic field between said cathode and anode structure, and perpendicular to the direction of motion of electrons from said cathode to said anode structure.

6. An electron discharge device comprising a cathode, an anode structure spaced from said cathode comprising a plurality of anode members, each of said anode members extending in a direction parallel to the electron emitting surface of said cathode for a distance substantially equal to a multiple of a quarter wave length of the operating frequency of said device, and a radial transmission line connected to said anode structure, adjacent anode members being connected to opposite bounding surfaces only of said transmission line.

7. An electron discharge device comprising a cathode, an anode structure spaced from said cathode comprising a plurality of anode members, each of said anode members extending in a direction perpendicular to the electron path between said cathode and said anode structure for a distance substantially equal to a multiple of a quarter wave length of the operating frequency of said device, a radial transmission line connected to said anode structure for coupling energy between said anode structure and said transmission line, adjacent anode members being connected to opposite bounding surfaces only of said transmission line, and means adjacent said

anode structure for producing a magnetic field between said cathode and anode structure, and perpendicular to the direction of motion of electrons from said cathode to said anode structure.

5 8. An electron discharge device comprising a cathode, an anode structure spaced from said cathode, means for cooling said anode structure comprising coolant passages in said anode members, and a substantially parallel plane radial transmission line extending inwardly from said anode structure.

15 9. An electron discharge device comprising a cathode, an anode structure spaced from said cathode comprising a plurality of anode members, and a radial transmission line comprising a pair of substantially planar conductors extending outwardly from said anode structure for coupling energy between said anode structure and said transmission line, adjacent anode members being connected to opposite bounding surfaces only of said transmission line.

20 10. An electron discharge device comprising a cathode, an anode structure spaced from said cathode comprising a plurality of anode members, and a planar radial transmission line extending toward a center axis from said anode structure, adjacent anode members being connected to opposite bounding surfaces only of said transmission line.

25 11. An electron discharge device comprising a cathode, an anode structure spaced from said cathode comprising a plurality of anode members, and a radial transmission line extending toward a center axis from said anode structure, and connected to said anode members adjacent the mid points thereof, adjacent anode members being connected to opposite bounding surfaces only of said transmission line.

30 12. An electron discharge device comprising a cathode, an anode structure spaced from said cathode comprising a plurality of anode members, each of said anode members extending in a direction parallel to the electron emitting surface of said cathode for a distance substantially equal to a multiple of a quarter wave length of the operating frequency of said device, means for cooling said anode structure comprising coolant passages in said anode members, and a radial transmission line extending inwardly from said anode structure, adjacent anode members being connected to opposite bounding surfaces only of said transmission line.

35 13. An electron discharge device comprising a cathode, an anode structure spaced from said cathode comprising a plurality of anode members, each of said anode members extending in a direction parallel to the electron emitting surface of said cathode for a distance substantially equal to a multiple of a quarter wave length of the operating frequency of said device, and a planar radial transmission line extending outwardly from said anode structure, adjacent anode members being connected to opposite bounding surfaces only of said transmission line.

40 14. An electron discharge device comprising a cathode, an anode structure spaced from said cathode comprising a plurality of anode members, each of said anode members extending in a direction perpendicular to the electron path between said cathode and said anode structure for a distance substantially equal to a multiple of a quarter wave length of the operating frequency of said device, and a planar radial transmission line extending inwardly from said anode structure, adjacent anode members being con-

nected to opposite bounding surfaces only of said transmission line.

15. An electron discharge device comprising a cathode, an anode structure spaced from said cathode comprising a plurality of anode members, each of said anode members extending in a direction perpendicular to the electron path between said cathode and said anode structure for a distance substantially equal to a multiple of a quarter wave length of the operating frequency of said device, and a radial transmission line extending outwardly from said anode structure, and connected to said anode members adjacent the mid points thereof, adjacent anode

members being connected to opposite bounding surfaces only of said transmission line.
